Francis Billingham for Midway Lampatty

UNITED STATES PATENT OFFICE.

FRANCIS BILLINGHAM, OF NEW YORK, N. Y.

DESIGN FOR SMOKE-BELL FOR LAMPS, &c.

Specification forming part of Design No. 7,749, dated September 8, 1874; application filed August 27, 1874.
[Term of Patent 7 years.]

To all whom it may concern:

Be it known that I, FRANCIS BILLINGHAM, of the city, county, and State of New York, have invented and produced a new and original Design for Smoke-Bells for Lanterns and Lamps, of which the following is a specification:

The nature of my design is fully shown in the accompanying photographic impression, to which reference is made; and consists of a smoke-bell made of the peculiar configuration represented, viz: Its upper portion *a a* is flat. From *a* to *b* is a curve giving the upper member *A* of the bell a concave conoidal shape. Below the member *A* is a plain fillet, *B*, extending from *b* to *c*. Below the line *c c* the

body *C* of the bell has an umbellate figure, its lower edge being cut into the petaliform pendants *D D*, separated by the perforations *e*, and having the points *ff* at their dependent ends.

What I claim as new is—

The design for smoke-bells for lanterns and lamps, as shown, the same consisting of the conoidal portion *A* separated by a fillet, *B*, from the umbellate portion *C*, the latter having its lower edge formed into pointed petals separated by the perforations *e*, all in the manner represented and specified.

FRANCIS BILLINGHAM.
In presence of—
Wm. H. POST,
E. P. GLEASON.
